PLATE

Sally L. Griggs, Springfield, Mass., assignor to Stanley Home Products, Inc., Westfield, Mass.,
a corporation of Massachusetts

Application May 7, 1952, Serial No. 19,628

Term of patent 14 years

(Cl. D44—15)

To all whom it may concern:

Be it known that I, Sally L. Griggs, a citizen of the United States, residing at Springfield, in the county of Hampden and Commonwealth of Massachusetts, have invented a new, original, and ornamental Design for a Plate, of which the following is a specification, reference being had to the accompanying drawings, forming part hereof:

Fig. 1 is a top plan view of a plate showing my new design.

Fig. 2 is a vertical sectional view taken on the line 2—2 of Fig. 1, and

Fig. 3 is a side elevational view thereof.

I claim:

The ornamental design for a plate, as shown.

SALLY L. GRIGGS.
